FIG. 1

I claim:

The ornamental design for a night-light, substantially as shown.
